(57) **CLAIM**

The ornamental design for a corner shower caddy as shown and described.

DESCRIPTION

FIG. 1 is a front perspective view of a corner shower caddy showing our new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a corner shower caddy shown in another state;

FIG. 10 is an enlarged view of portion 10 shown in FIG. 1; and,

FIG. 11 is an enlarged view of portion 11 shown in FIG. 2. The dash-dash broken lines in the drawings depict portions of the corner shower caddy that form no part of the claimed design. The dot-dash broken lines represent boundaries of the enlarged portions and form no part of the claimed design. The dot-dot-dash broken lines represent boundaries of the symbolic break and form no part of the claimed design. The corner shower caddy is shown with a symbolic break in its height. The appearance of any portion of the article between the break lines forms no part of the claimed design.

1 Claim, 11 Drawing Sheets
